UNITED STATES PATENT OFFICE.

SALI LOEWENSTEIN, OF NEW YORK, N. Y.

DESIGN FOR A LADY'S COLLAR.

SPECIFICATION forming part of Design No. 15,015, dated May 27, 1884.

Application filed February 5, 1884. Term of patent 3½ years.

To all whom it may concern:

Be it known that I, SALI LOEWENSTEIN, a citizen of the United States, residing in the city of New York, in the State of New York, 5 have invented and produced a new and Original Design for Ladies' Collars, of which the following is a specification, reference being had to the accompanying drawings, forming a part thereof.

10 My design refers more particularly to collars for ladies' wear; and it consists in the representation of plaits or ruffles in the body A and edge C of the collar in alternate blocks or bands of contrasting colors, with the plain 15 space B between the edge and body, as shown in the drawings.

The design may be modified in some particulars without changing its essential features, as the alternate blocks of contrasting 20 colors may be confined to the body of the collar, with the edge of a solid color corresponding with one of the colors in the body, as illustrated in Fig. 1; or the body of the collars may be of a solid color, and the edge of alternate blocks of contrasting colors, as shown in Fig. 25 2; or both the edge and body may be of alternate blocks of separate colors; and the representation of the plaits or ruffles may be vertical, as shown in Figs. 1 and 2, or inclined at an angle, as is seen in Fig. 3, without changing 30 my design, the essential feature of which is the appearance or representation of the plaits or ruffles in alternate blocks of contrasting colors.

I claim—

35 The design for ladies' collars herein shown and described, consisting of the representation of plaits or ruffles in alternate blocks or bands of contrasting colors in the body and edge of the collar, with the representation of 40 the plain space between the body and edge.

SALI LOEWENSTEIN.
